CLAIM

The ornamental design for a square-shaped wooden box, as shown and described.

DESCRIPTION

FIG. 1 is a perspective view of a square-shaped wooden box showing the new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof; and

FIG. 7 is a front elevation view thereof; and,

FIG. 8 is a perspective view thereof wherein the wooden box is in an open configuration.
